UNITED STATES PATENT OFFICE.

JOHN S. SKELLY, OF MONONGAHELA, PENNSYLVANIA, ASSIGNOR TO INTERNATIONAL COMBUSTION ENGINEERING CORPORATION, A CORPORATION OF DELAWARE.

AUTOMATIC STOKER.

Application filed August 24, 1923. Serial No. 659,030.

This invention relates to automatic stokers and particularly to underfeed stokers.

An object of the invention is to produce a stoker of the type specified in which improved means are employed for delivering fuel to the stoker, for supporting and propelling the fuel through the combustion chamber of the stoker, and for discharging the ash or refuse material from the combustion chamber.

In underfeed furnaces, the fuel is delivered to the furnace or to the combustion chamber of the furnace, in such a way that it is subjected to the sensible heat of combustion within the furnace before it is supplied with sufficient air to promote combustion. Under such conditions, the fresh or green fuel on being introduced into the furnace is subjected to a coking operation during which the volatile hydrocarbon gases are distilled off and pass through previously delivered fuel and a portion of the burning fuel bed in its travel toward the stack or the combustion space within the furnace above the fuel bed.

Under such conditions, it is desirable to break up the coked mass resulting from the coking operation, as it moves upwardly into the air delivery zone. I have found that it is desirable to control this breaking up process to a greater extent than in existing stokers. I accomplish this in the stoker illustrated by employing a special form of fuel supporting elements so located and arranged with relation to the retort that effective breaking up of the coked mass issuing from the retort is somewhat delayed as the fuel progresses toward the rear, or refuse delivery end of the stoker. With such apparatus it is possible to materially increase the fuel burning capacity of the furnace, per square foot of grate surface, and to obtain substantially complete combustion of the fuel without producing smoke.

A further object of the invention is, therefore, to produce a furnace equipped with an automatic stoker in which means are employed for improving the fuel-burning conditions by controlling the breaking-up of the coked mass issuing from the retort in such a way that a complete breaking up of the mass is deferred for an appreciable period as the coked mass progresses toward the rear or the ash discharge mechanism.

Other objects not specifically specified

will be made more apparent throughout the further description of the invention.

In the drawings accompanying and forming a part hereof, Figure 1 is a longitudinal sectional elevation of a stoker embodying my invention. Fig. 2 is a fragmental sectional elevation of a modified form of grate bar forming a detail of the present invention. Figure 3 is a side elevation of the stoker illustrated in Fig. 1, and illustrates the particular form of operating mechanism employed. Fig. 4 is a fragmental perspective view of the apparatus illustrated in Fig. 1.

The stoker illustrated as an embodiment of my invention includes a grate made up of two series—5 and 6—of rearwardly extending grate bars located in parallel relation. A transversely extending retort 7 is located at the front of the stoker and extends substantially the entire width of the grate. Fuel is delivered to the retort on the side remote from the grate through a fuel-receiving opening which extends substantially the entire width of the grate. A fuel hopper 9 is located at the front of the furnace and extends across the furnace substantially the entire width of the fuel-receiving opening of the retort. Reciprocable fuel-feeding means 10 are located below the hopper in such relation therewith and with the opening in the retort, that fuel issuing from the hopper is forced into the retort, by the reciprocations of said means. The fuel-feeding means consists of a series of reciprocable plungers 10 which extends substantially the entire length of the opening into the retort. These plungers are moved back and forth across the mouth of the hopper 9 by a continuously operating mechanism hereinafter more fully described.

As shown in the drawings, the retort 7 is provided with a horizontal floor 11, extending the entire length of the retort and of such width that it projects through the fuel receiving opening formed in the front wall 13 of the stoker and forms the bottom of a passage 12 into which fuel from the hopper is delivered and through which fuel is propelled into the retort by the action of the plungers 10. The passage 12 is commensurate in width with the length of the retort 7 and is so located and arranged that there is no clear line of demarcation between it and

the retort. As shown the passage is located between the floor 11 and a top plate 14, which is inclined upwardly in the direction of the fuel feed, thereby providing a passage 5 with gradually diverging walls which increases in depth from the fuel admission end toward the retort and is deeper at the retort end than the retort.

The rear of the retort is defined by the 10 forward ends of the grate bars comprising the series 5. The height of these grate bars above the floor 11, therefore, defines the depth of the retort. As shown, the series 5 is made up of alternately arranged moving 15 and stationary bars 15 and 16, which extend from the retort 7 toward the rear of the stoker and are so constructed and arranged that their rear portions are inclined downwardly, in the direction of fuel travel, and 20 deliver fuel onto the second series 6.

As shown the grate bars 15 and 16 are supported at their forward ends on the upper edge of the floor 11 and at their rear ends on a transversely extending member 17, 25 forming a part of the supporting structure of the stoker. These grate bars are hollow, each being provided throughout their length with an air delivery passage 18 having an inlet port at the lower side near the forward 30 end of the bar, and an outlet at the lower side near the rear end of the bar. The forward end of each bar is substantially wedge shaped and so formed that it presents an upwardly-inclined surface α to the fuel issuing from the retort 7. This surface terminates in a substantially horizontal fuel supporting surface γ which extends toward the rear of the stoker. The horizontal surface of each bar is followed by a downwardly-inclined surface β which is continuous 35 with the horizontal fuel supporting surface but which abruptly falls away from the surface γ so as to provide a well-defined angle or shoulder over which the fuel is 40 propelled as it leaves the horizontal surface of the bar. The lower ends of the bars of the series 5 are substantially wedge shaped but are rounded off so as to form a more or 45 less abrupt toe 19 which engages the top surface of the one of the bars of the series 6 and 50 has the effect of a pusher for aiding the rearward propulsion of fuel over these bars.

From the foregoing it will be apparent 55 that each grate bar of the series 5, is provided with substantially wedge shaped ends and that the fuel supporting surface between the ends comprises in effect surfaces which extend at a more or less abrupt angle to each other and thereby provide a well 60 defined shoulder over which the fuel passes in moving from one part of the supporting surface to the other.

The series 6 includes alternately-arranged 65 moving and stationary grate bars 21 and 22 which extend in the direction of fuel travel

and which are supported at their forward ends on the member 17 and at their rear ends on a partition wall 23. The wall 23 forms a part of the stoker-supporting structure and also separates an ash-receiving receptacle 24 formed at the rear of the stoker from an air chamber 25 located below the bars 21 and 22 of the series 6. 70

Each of the grate bars 21 and 22 is hollow, being provided with an air passage 20 which extends substantially the length of the bar and is provided at the forward end with an air inlet port opening through the bottom of the bar and at the rear end with an air delivery port also opening through the bottom of the bar. Each bar is also so constructed that its forward end provides a substantially horizontal fuel supporting surface which terminates in a downwardly-inclined fuel-supporting surface extending to the rear end 80 of the grate bar. The inclination of the rear portion of each grate bar is, however, substantially less than the inclination of the rear portion of each of the grate bars 15-16. 90

The space below the grate bars is divided into two air chambers 25 and 26. As has been stated, the chamber 25 is located below the bars of the series 6. The chamber 26 is located below the bars of the series 5. Each 95 of these air chambers receives air under pressure from a conduit or passage 27 but the air traverses the air passages of one of the series of grate bars before it enters either air chamber. As shown in Fig. 1, an upwardly extending branch passage 28 leads off from the conduit 27 and delivers air under pressure to the passages 18 of the grate bars 15 and 16. This passage 28 is bounded by transversely-extending partition 100 plates 29 and 30. The upper end of the passage 28 terminates in a transversely extending port located between the rear edge of the floor 11 and a transversely-extending member 31 which forms a part of the supporting structure of the stoker. The port registers with the inlet ports of the passages 18 of the grate bars 15 and 16 and consequently the chamber 26 receives air from the passage 28 after it has traversed the hollow grate bars 15 and 16. With this arrangement, the grate bars are cooled by the incoming air and the major portion of the air delivered to the fuel bed is therefore 110 preheated. 115

The grate bars of the series 5 are spaced apart a sufficient distance to provide air-delivery spaces between them through which air delivered to the chamber 26 passes upwardly into the fuel bed. 125

Air is delivered to the chamber 25 through a branch passage 32 and the air passages 20 of the bars 21 and 22. The branch passage 32 is located between partition plates 33 and 34 which respectively separate the passage 130

from the chambers 26 and 25. The upper end of this passage terminates in a transversely-extending port formed between a support member 35 of the stoker structure and the support member 17. The bars of the series 6 are also spaced so as to provide air passages between them through which preheated air from the chamber 25 is delivered to the portion of the fuel bed supported by the bars.

Air is also delivered directly to the fuel bed from the passage 32 through the spaces between the grate bars. In addition to this, air is delivered directly from the passages 15 20 of each grate bar 21 and 22 to the fuel bed. This is accomplished by providing air ports 36 in the fuel-supporting surface of each of the grate bars. As shown, the air ports are preferably so arranged that air is delivered at the forward ends only of these bars and, in addition, the ports are so spaced that the greater portion of the air from the passage 20 is admitted at a point immediately adjacent to the lower ends of the bars 25 15 and 16.

One of the features of the present invention is the arrangement of the air ports in the fuel-supporting surfaces of the bars 15 and 16. As shown in Fig. 1, each of these bars is provided with air ports 37, adapted to deliver air from the passages 18 to the fuel bed. The ports are arranged in the forward portion of the bars only and are preferably so spaced that the quantity of air delivered through these to the fuel bed increases as the fuel progresses toward the rear of the stoker. It will also be apparent that some air is delivered to the fuel bed directly from the passage 28 through the spaces between the grate bars.

The passages 28 and 32 are respectively provided with dampers 38 and 39 which may be independently controlled.

It will thus be apparent that the delivery of air to the front and rear portions of the stoker may be independently controlled and that, in addition to this, the air is so delivered to the fuel bed that two distinct zones of increased air supply are provided. Each of these zones is located near the forward end of one of the two series of grate bars and the delivery of air to each is controllable independently of the other.

In Fig. 2, I have shown a modified form of grate bar which may be employed in place of the bars 15 and 16. As illustrated, this bar is provided with a wedge shaped forward end which presents a steep and somewhat elongated inclined surface x' to the fuel issuing from the retort. This surface terminates in a relatively short substantially horizontal fuel-supporting surface y' which terminates in a downwardly inclined surface z' of such abrupt inclination as to present a well-defined shoulder over which the

fuel passes in moving onto the rear portion of the grate bar. The rear portion of the grate bar is inclined downwardly toward the rear so as to provide a downwardly-inclined fuel-supporting surface z'' . The angle of this surface is, however, materially less than that of the surface z' . As shown, the surfaces x' and y' are provided with air ports 37', through which air is delivered from the passage 18 into the fuel bed.

Another feature of my invention is the fuel-disposal mechanism located at the rear end of the stoker and employed in connection with the receptacle 24. As shown, a pivotally mounted ash-regulating gate 41 is provided immediately below the rear ends of the bars 21 and 22. This gate is capable of being tilted to different angular positions for the purpose of varying the angle of delivery to a rotating grinder 43, which rotates in the direction indicated by the arrow. The principal function of this tilting gate is to deliver refuse material discharged from the grate bars 21 and 22 to the grinding roll or to by-pass the grinding roll so such material is dropped from the bars 21 and 22 into the bottom of the receptacle 24. To this extent the gate functions as a dump grate, since it may either be elevated to the position shown in full lines in Figure 1, where it acts as a fuel-bed support member, or it may be tilted to the dotted-line position for the purpose of dumping the accumulation of ash and clinker into the bottom of the receptacle. In order that I may employ the gate 41 in this way and also adjust it to different angular positions, I preferably operate it by means of a worm 44 and worm wheel segment 45, shown in Fig. 3. The segment 45 is mounted on the shaft of the gate and is located outside but adjacent to one side wall of the stoker. The worm 44 is preferably operated by hand by means of a ratchet-and-pawl mechanism, not shown.

The grinder 43 is of the usual construction and, as illustrated, consists of toothed discs mounted on a square shaft. It preferably rotates at the top toward the bridge wall 45^a so that the clinker breaking effect is accomplished between it and the bridge wall. For the purpose of rendering the grinder more efficient in operation, I employ what may be termed a "grinder back" 46, which is located immediately above the grinder so that refuse material passing over the grinder must pass between it and the back. As shown, the back 46 is hollow and is preferably water-cooled. This arrangement has two advantageous features. It prevents the sticking of clinker to the rear wall of the stoker above the grinder and it also has some cooling effect on the clinker and ash passing to the grinder and into the bottom of the receptacle. The receptacle is

provided with a spiral conveyor 47 which is preferably operated by the operating mechanism of the stoker so as to remove the refuse material delivered to the receptacle at about 5 the rate of its delivery to the receptacle.

Another feature of my invention is that the front plate 14, forming the top of the fuel-delivery passage 12, is air-cooled.

This is accomplished by making the plate 10 a part of an oblong enclosure 48 to which air is delivered and from which air is discharged into the combustion chamber of the furnace through conduits or passages 49. As shown, the passages 49 extend through 15 the front wall 13 of the furnace some distance above the fuel-supporting grate.

The fuel-delivery means 10 preferably consists of a number of plungers located adjacent to each other and so arranged that the 20 passage 12 throughout its entire length is a fuel-delivering passage. While a single plunger of the length of the passage could be employed, for convenience of manufacturing and also for convenience of operation, 25 I preferably employ sectional plungers and an operating mechanism so arranged that some of the plungers are moving through the fuel feeding stroke toward the retort while others are being withdrawn from the 30 retort.

As illustrated, each plunger or plunger section is operated by means of a reciprocating carriage 51 which is mounted on a suitable frame at the front of the stoker 35 and is operatively connected to the plunger by means of a detachable link 52. As shown, the link is pivotally secured to the carriage and is provided near its free end with a slot which is adapted to engage a pin 53 carried by the plunger 10, and which permits the link to be detached from the 40 plunger.

Each carriage is actuated by means of a 45 crank 54 carried by a crank shaft 55. The crank is located within the carriage and the walls of the carriage are so constructed that they are first engaged at one side by the crank for the purpose of moving the carriage through a fuel-feeding stroke, and then at 50 the other side for the purpose of retracting the carriage. Any suitable means may be employed for driving the shaft 55 but, as illustrated, it is driven from a drive shaft 56 through the agency of intermeshing 55 gears 57 and 57a.

A feature of my invention is that the moving bars 15 of the upper series of bars are aligned with and cooperate with the stationary bars 22 of the lower series, whereas the moving bars 21 of the lower series are aligned with and cooperate with stationary bars 16 of the upper series. The operating mechanism of the moving bars of each series is preferably driven from the shaft 55. As 60 shown in the drawings, the moving bars of

the series 5 are actuated by means of a rocking arm 58 which extends transversely of the bars and is operatively coupled thereto by means of lugs 59 formed integrally with the bars. A similar arrangement of apparatus is employed in connection with the moving bars of the series 6 and, as illustrated, these bars are actuated by means of a rocker arm 60 and lugs 61 associated with the moving bars. As shown in Fig 3, 70 the operating shafts 62 of both the arms 58 and 60 project through a side wall of the furnace and each is provided with an operating lever 63. These levers are actuated through interconnecting links 64 and 65 by 75 means of a lever 66. The lever 66 is pivoted at a point intermediate its ends and is oscillated by a crank 67 mounted on the shaft 55 and connecting rod 68. The lower end of the lever 66 is slotted to receive a pin 69 carried by the link 65 and is provided with ratchets 70 adapted to be engaged by a pawl, not shown, for the purpose of locking the link in different positions along the lever and thereby varying the throw of the rocker 80 bars 58 and 60. As shown in the drawings, the conveyor 47 is actuated by means of a sprocket 71, chain 72 and sprocket 73. The sprocket 71 is mounted on the conveyor shaft and the sprocket 73 is mounted on the 85 drive shaft 56.

The operation of the stoker is as follows: The reciprocating plungers 10 force fuel, delivered from the hopper 9, forwardly into the passage 12 through the passage and into the retort. The crowding action of the fuel entering the retort completely fills the diverging portion of the passage, and at the time the divergence of this passage prevents undue packing of the fuel to such an extent 90 as to impede the delivery of fuel into the retort. The fuel so delivered by the plungers fills and piles up in the retort until the retort overflows onto the grate bars of the 95 series 5. After the fuel is established on the fuel-supporting grate, the fuel leaving the retort is crowded upwardly by oncoming fresh fuel so that the fuel bed is built up from below and to a considerable height 100 above the retort and above the forward ends 105 of the grate bars 5 and 6. The rearward travel of the fuel issuing from the retort is maintained by the propelling action of the reciprocating or moving bars of each series. 110

The motion imparted to these bars is a 115 horizontal reciprocation so that each moving bar first moves rearwardly beyond the fuel-supporting surfaces of the stationary bars. With the bars 15 and 16 constructed as disclosed in Fig. 1 or in Fig. 2, the propelling 120 action of the downwardly inclined rear portions of the bars is quite marked, whereas the horizontal fuel-supporting portions of the bars occasion little propelling effect and practically no breaking up of the fuel bed. As 125 130

the fuel issues from the retort, it is subjected to the breaking-up action of the moving bars 15 as they move forwardly into the confines of the retort as defined by the forward ends 5 of the stationary bars and rearwardly out of the retort as so defined. This action is sufficient to aid in the rearward propulsion, and upward lift of the fuel and to prevent jamming of the fuel in the retort. It also 10 facilitates the delivery of air to the coked mass issuing from the retort but it does not occasion a complete or thorough breaking up of the coked mass. The fuel located on the horizontal portion γ of the grate bars 15 and 15 16 is subjected to little or no propelling action and to no breaking up action; consequently, the fuel bed builds up over the horizontal portions and its rearward progress is primarily occasioned by this building-up action. 20 This produces a relatively deep fuel bed at the forward end of the stoker, which is desirable. It is, however, desirable to break up this fuel bed as the fuel starts to move more rapidly across the grate so that it will 25 thin out toward the rear end of the stoker. This breaking-up action is effectively accomplished by employing bars so formed that the fuel leaving the horizontal portion passes over a well-defined shoulder and also moves 30 down a relatively steep incline composed of alternately arranged stationary and moving bars.

The reciprocations of the moving bars, as 35 well as gravity, acts to break up the fuel bed and to accelerate its rearward movement of the fuel toward the rear of the stoker. The grate bars comprising the series 6 to some extent check the rearward propulsion of the fuel due to the fact that the inclination is 40 materially less than the inclination of the bars of the series 5. The moving bars of this series, however, occasion a uniform feed of fuel and prevent an undesirable thickening of the fuel bed. The entire arrangement 45 of elements occasions an effective burning of fuel by maintaining a fuel bed of desired contour and by delivering excess air to certain portions of the fuel bed.

As has been described the ash and clinker 50 are delivered to the clinker grinder roll 43 across the gate 41 and this gate may be dropped for the purpose of by-passing the grinder roll if desired.

While I have described, what I now consider 55 to be the preferred embodiment of my invention it will be apparent to those skilled in the art that various additions, omissions, changes and modifications may be made in the apparatus illustrated without departing 60 from the spirit and scope of my invention as set forth by the appended claims.

What I claim is:

1. In combination in a stoker, a retort extending substantially entirely across the 65 front of the stoker, a series of alternately

arranged moving and stationary grate bars located in parallel relation and extending from said retort toward the rear of the stoker, each of said bars having a wedge shaped forward end provided with air delivery apertures in the fuel supporting surface thereof, a substantially horizontal fuel supporting surface located immediately adjacent to the wedge shaped end and having air delivery apertures formed therein and a 70 downwardly inclined fuel supporting surface extending from the horizontal surface toward the rear end of the stoker, and means for feeding fuel through said retort and on to the forward ends of said grate bars. 80

2. In combination in a stoker, a retort extending substantially entirely across the front of the stoker, a series of alternately arranged, moving and stationary grate bars, located in parallel relation and extending from said retort toward the rear of the stoker, each grate bar of said series having a wedge shaped forward end provided with air delivery apertures in the fuel supporting surface thereof, a substantially flat fuel supporting surface extending at an angle to the fuel supporting surface of the wedge shaped end and a fuel supporting surface extending downwardly at an abrupt angle from the last mentioned fuel supporting surface, 90 means for propelling fuel transversely across said retort and on to the wedge shaped ends of the said bars and means for reciprocating the moving bars of the series. 95

3. In combination in a stoker a retort extending across the front of the stoker, a series of longitudinally arranged, moving and stationary grate bars, located in parallel relation and extending from said retort toward the rear of the stoker, each grate bar of the series having an upwardly inclined forward fuel supporting surface, a downwardly inclined rear fuel supporting surface and an intermediate substantially horizontal fuel supporting surface contiguous to both said first mentioned surfaces, a second series of alternately arranged moving and stationary grate bars moving in parallel relation and extending from the rear ends of the first series toward the rear of the stoker, the bars of the second series having fuel supporting surfaces extending at an angle to the rear supporting surfaces of the bars of the first series and being provided with air delivery apertures in the forward portions thereof. 110 105 115

4. In combination in a stoker, a retort extending across the front of the stoker, a series of alternately arranged moving and stationary grate bars located in parallel relation and extending from the retort toward the rear of the stoker, each of said grate bars having three substantially flat fuel supporting surfaces, located at an angle one to the other whereby the direction of the travel of the fuel varies as the fuel moves longitudi- 120 125 130

- 8
- nally of said bars, means for delivering fuel transversely through said retort and on to said bars, and means for reciprocating the movable bars of the series.
5. In combination in a stoker, a retort extending across the front of the stoker, a series of grate bars extending in parallel relation from said retort toward the rear of the stoker, a reciprocating means extending substantially entirely along the length of said retort for delivering fuel thereto, each of the grate bars of said series having a wedge shaped forward end, a substantially horizontal fuel supporting surface immediately adjacent said wedge shaped end, and a downwardly inclined fuel supporting surface, immediately adjacent said horizontal surface, and means for reciprocating grate bars of said series.
6. In combination in a stoker, a retort extending across the front of the stoker, a series of grate bars located in parallel relation and extending from the front toward the rear of the stoker, each grate bar of the series having a wedge shaped forward end provided with air delivery apertures, a downwardly inclined rear end and an extended substantially flat intermediate fuel supporting surface provided with air delivery apertures and located at an angle to the adjacent fuel supporting surfaces of said bar, whereby fuel traversing the bar is subjected to a breaking action in moving from one fuel supporting surface to the other.

In testimony whereof, I have hereunto subscribed my name this 7th day of August, 1923.

JOHN S. SKELLY.
